ELECTRIC TATTOOING DEVICE

Filed Jan. 30, 1929

UNITED STATES PATENT OFFICE.

PERCY WATERS, OF DETROIT, MICHIGAN.

ELECTRIC TATTOOING DEVICE.

Application filed January 30, 1929. Serial No. 336,219.

My invention relates to an electrical marking device or tattooing instrument, and it has for its object to provide an improvement in devices of this character, the peculiar and novel construction of which is pointed out in the following specification and claims, and illustrated in the accompanying drawing, in which—

Figure 1 is a perspective view of the device 10 in its entirety.

Figure 2 is a detail elevational view partly in section of the needle bar housing.

Figure 3 is a perspective partial view of the device in a person's hand showing the 15 manner of operating the finger switch.

Figure 4 is a detail sectional view taken on line 4—4 of Figure 2.

Figure 5 is a detail sectional view taken on line 5—5 of Figure 2.

Figure 6 is an elevational view of the 20 various types of needles used in the device.

Figure 7 is a partial detail elevational view of the spark shield as applied to the device,

Figure 8 is a perspective view of the spark 25 shield.

Referring to the drawing, 1 denotes an L-shaped frame of malleable iron having a pair of electro-magnets 2 mounted in an upright position on the horizontal leg 3 of the frame 1 30 and secured thereto in any conventional manner. Extending from one of the sides and intermediate the ends of the horizontal leg 3 is a seat 4 on which a vertical binding screw 5 is adapted to be secured. Adjacent the seat 35 4, and rigidly secured to the horizontal leg is a standard 6 the purpose of which is to be hereinafter described. The horizontal leg 3 terminates in a split portion 7, having a hole 8 formed therein for the reception of the end 40 of a barrel or needle bar housing 9, which is adapted to be securely clamped to said frame 1 by means of a screw 10 passing through the split portion 7.

The vertical leg 3' of the frame 1 terminates 45 in a right-angle rearwardly extending projection 11 adapted to have secured thereto through the medium of the screw 12 a leaf spring 13, having a flat portion 14 and an angular tapered portion 15. An armature 50 bar 16 is arranged in spaced relation to the armatures 17 of the electromagnets 2, and is secured to the under side of the spring 13 by means of the screw 18, said armature bar 16 having formed on its free end a stud 19.

Secured to the upper end of the standard 6 55 and perpendicular thereto is a binding post 20 having a contact screw 21 extending therethrough and contacting the tapered end of the spring 13. A spark shield 22 of sheet metal or other suitable material provided 60 with a threaded opening 23 is secured in threaded engagement with the contact screw 21 to the under side of the binding post 20, the flared end 24 of the shield 22 extending in front of the point of contact between the 65 contact screw 21 and spring 13, as clearly shown in Figure 7.

The barrel or needle bar housing comprises a metallic tubular member 9 terminating in a tapered portion or well 25. A finger switch 70 comprising a rubber cylinder 26 having embedded in its wall a contact bar 27 adapted to extend therefrom, is in turn molded or otherwise secured to the barrel 9. Projecting from the inner end of the contact bar 27 is a 75 binding screw 28 to which one terminal 29' of the electric cable 29 is secured, the other terminal 29" being fastened to the binding post 5.

The barrel 9 is adapted to receive any one of 80 the three types of needles A, B or C illustrated in Figure 6. Each needle comprises a needle bar 30 terminating in an eye 31, the other end of said needle bar having soldered or otherwise secured thereto a cluster of needles 85 to be used in outlining as shown in A, or a point of tool steel so shaped as to be adapted for engraving or etching, as shown in B, or another cluster of fine needles adapted for shading or filling in colors, as shown in C. 90 Each needle bar 30 is inserted into the barrel through the hole 8, the eye 31 of said needle bar 30 being slipped over the stud 19 on the armature bar 16. To retain the needle bar 30 on the stud 19 a rubber band 32 or other 95 suitable resilient means is provided, said rubber band 32, extending from the needle bar 30 to the vertical leg 3' which has suitable notches 3'' provided thereon for the reception of said rubber band.

One terminal 33 of the electro-magnets 2 is connected to the binding post 5, the other terminal 34 being directly connected to the metallic frame as at 35. Pressure applied on the contact bar 27 by means of the forefinger, see Figure 3, closes the circuit thereby causing the electro-magnets to actuate the make and break mechanism, the oscillations 100 105

of the armature bar 16 causing said needle bar 30 to oscillate in a like manner; the current being supplied either from a dry-cell battery or from a transformer connected to 5 a house circuit.

When the device is to be operated as a tattooing machine the coloring medium or ink is put in the lower tapered portion or well 25 of the barrel 9, through the hole 8.

10 It will thus be seen that I have fully described and illustrated an electric tattooing instrument that can be readily used for the marking or tattooing of the ear of a fur animal as well as for an electro engraving 15 purpose and for all other uses that instruments of this character are generally utilized.

What I claim as new and desire to secure by Letters Patent is:—

1. In an electric marking device, a metallic 20 frame, an electro-magnet secured thereto, an armature bar yieldingly connected to said frame and adapted to be actuated by said electro-magnet to operate a make and break control, a barrel secured to said frame, a 25 needle bar in said barrel and connected to said armature, resilient means engaging said frame and needle bar to retain said needle bar in operative engagement with said armature, and a finger control switch on said barrel, 30 rel adapted to close the circuit to energize said electro-magnet.

2. In an electric marking device, an L-shaped metallic frame comprising two legs arranged at right angles to each other, a 35 plurality of electro-magnets secured to the horizontal leg, an adjustable contact screw carried on a vertical standard constituting an integral part of said horizontal leg, a make and break mechanism secured to the vertical 40 leg in engagement with said contact screw, an armature bar having a forwardly extending lug secured to said mechanism, tubular guide means, a needle bar comprising an eye on its upper end in engagement with said lug 45 and positioned within said guide means, resilient means retaining said needle bar in

position, and a finger switch mounted on said tubular guide means.

3. In an electric marking device, an L-shaped metallic frame comprising two legs 50 arranged at right angles to each other, the free end of the horizontal leg being split and having a hole adjacent its edge, a tubular member adapted to fit within said hole, and a screw bolt adapted to draw said split portions together to clamp said tubular member in place.

4. In an electric marking device, a frame, a needle bar, an electric actuating means therefor, a tubular metallic guide means for 60 said needle bar, a rubber sleeve on said tubular member, a contact bar embedded therein and extending a short distance outwardly thereof, means to connect one terminal of an electric circuit to said contact bar, means 65 to connect the other terminal to the frame, whereby when said contact bar is depressed to contact the tubular member the circuit will be closed and thereby actuating the needle 70 bar.

5. In an electric marking device, an L-shaped metallic frame, a plurality of electro-magnets mounted on the horizontal leg of said frame, a standard on said horizontal leg, a leaf spring connected to the vertical 75 leg of said frame, an armature bar secured to the under side of said leaf spring intermediate its ends and adapted to be actuated by said electro-magnets, an adjustable contact screw carried by said standard adapted 80 to engage the end of said spring, said metallic frame constituting part of an electric circuit, a finger control means to close said circuit to energize said electro-magnets, a spark shield mounted on said standard, marking means connected to said armature bar, guide means therefor attached to said frame, and resilient means retaining said marking means in operative engagement with said armature 85 bar.

In testimony whereof I affix my signature.
PERCY WATERS.
